UNITED STATES PATENT OFFICE.

OSCAR F. FORSBERG, OF CHICAGO, ILLINOIS, ASSIGNOR TO WESTERN ELECTRIC COMPANY.
OF CHICAGO, ILLINOIS, A CORPORATION OF ILLINOIS.

LOCK-OUT SWITCH FOR PARTY TELEPHONE-LINES.

No. 873,362.

Specification of Letters Patent.

Patented Dec. 10, 1907.

Application filed October 5, 1906. Serial No. 337,510.

To all whom it may concern:

Be it known that I, OSCAR F. FORSBERG, citizen of the United States, residing at Chicago, in the county of Cook and State of Illinois, have invented a certain new and useful Improvement in Lock-Out Switches for Party Telephone-Lines, of which the following is a full, clear, concise, and exact description.

10 My invention relates to a lock-out switch for party telephone lines, and has for its object to provide an improved and simplified device whereby any two or more stations of a party line may be connected for conversation 15 to the exclusion of other stations on such line. The improvements of my invention are applicable to a switching device wherein an electromagnetically operated stepping lever is arranged when rocked in one direction to 20 advance a ratchet, which, as it leaves normal position, opens the talking circuit of the station where the same is located. When the ratchet has been advanced a number of steps corresponding to the number of the station 25 where it is located, mechanism is brought into play to cause the stepping arm when given a movement in the opposite direction to close contact springs to complete the talking circuit of the station in question. The 30 ratchet may then be advanced to the end of its movement, when it will bring into service mechanism which, when the lever is caused to again rock in said opposite direction, at the termination of the conversation, will 35 cause said lever to release the ratchet, which thereupon returns to normal position, opening the said contact springs, and restoring the normally existing talking circuit.

My invention is directed towards improvements in the means for operating the contact springs when the stepping lever is rocked in the opposite direction, after the ratchet has been advanced a predetermined distance, and also towards the provision of improved 45 means for causing the ratchet at the end of its movement, to effect its release by the movement of the stepping lever in the said opposite direction.

I preferably provide an arm, operated by 50 the ratchet after being advanced a predetermined distance, adapted to cause the stepping lever in its reverse movement to actuate contact mechanism. Said arm is again operated by the ratchet at the end of its movement, and the arm thereupon causes the step-

ping lever, when given another reverse impulse, to remove the retaining mechanism from the ratchet, and permit the restoration of the device to normal condition.

A feature of the invention consists in rendering adjustable the means by which the ratchet operates said arm to cause the stepping lever to operate said contact mechanism, so that the ratchet may be caused to operate the arm at any desired point in its ad- 60-65

I will describe my invention more particularly by reference to the accompanying drawings, which represent an embodiment of my invention, reserving, however, for the ap- 70-75

plied claims a statement of the parts, improvements and combinations which I consider novel with me.

In the drawings, Figure 1 is a front view of a switching device embodying my invention; Fig. 2 is a side view thereof; Fig. 3 is a front view, with the arm operated to bring the foot of the stepping lever into position to engage the operating lever of the contact springs, and showing the stepping lever rocked in a 80 direction to cause the foot to move said operating lever; Fig. 4 is a partial front view showing the arm operated to bring the foot into position to engage the finger of the retaining pawl, with the stepping lever rocked to cause 85 said foot to move said finger and remove the retaining pawl from the ratchet; and Fig. 5 is a detail vertical sectional view on line 5-5 of Fig. 3.

The same letters of reference are used to 90 designate similar parts wherever they are shown.

A polarized electromagnet 1 is provided with a tilting armature 2 which controls the rocking of the stepping lever 3 of the ratchet 4, said lever 3 carrying a stepping pawl adapted to engage the teeth of said ratchet when the lever 3 is rocked in one direction—to the left in Fig. 1. An arm 5 is pivoted upon the framework of the device, and is 100 adapted to be operated by the ratchet 4 when advanced a predetermined distance to cause the stepping lever 3, when rocked in a reverse direction—that is, to the right in Fig. 1—to actuate contact mechanism which may 105 control the talking circuit at the station where the switch is located. Said contact mechanism may comprise springs 6 adapted to be closed by a rocking lever 7. The lever 7 carries at its upper end an angular projection 110

8 adapted to be engaged by a sliding foot 9 mounted upon the stepping lever 3, when said foot is brought into operative relation to said projection 8, and when the lever 3 is 5 rocked to the right.

The arm 5 is adapted to move the foot 9 into operative relation to said projection 8 when the ratchet advances a predetermined distance, and to this end such arm 5 may 10 carry a pin 10 riding in a concentric slot 11 in the ratchet 4, and adapted to be engaged by a spur 12 secured to the ratchet and projecting into the path of said pin. Said spur is arranged to be set at any desired position in 15 the path of said pin so as to engage the same at any desired point in the advance of the ratchet and rock the arm 5 to cause the same to lift the foot 9 and bring the same into operative relation to a projection 8 of the operating lever 7, so that when the stepping lever 3 is moved to the right the lever 7 will be operated to close contact springs 6. The spur 12 may be loosely mounted on the shaft of the ratchet 4, and a binding screw 13 is 20 arranged to pass through a concentric slot 14 in the ratchet to secure the spur to said ratchet and cause the same to project into the path of pin 10 at any desired point. Thus if the switching device were located at station No. 4 of a party line, the spur 12 would be set to engage the pin 10 when the ratchet had been advanced four steps. It should be stated at this point that each station of a 25 party line employing such a lock-out system would be provided with a switching device, and the ratchets of all the switching devices would be simultaneously operated; and it will be seen that when such ratchets have been advanced four steps the arm 5 at station No. 4, alone, would be operated to 30 bring the foot 9 into operative relation to the operating lever 7 of the contact springs 6, so that when the levers 3 of the switching devices are operated in a reverse direction, that 35 is, to the right in Fig. 1, the contact springs 6 at station No. 4, alone, would be operated.

A spring actuated retaining pawl 15 is provided for the ratchet, said pawl having a finger 16 extending upwardly parallel to the operating lever 7, and having an angular projection 17 lying above the projection 8 of the lever 7, and the arm 5 is arranged to be operated by the ratchet at the end of its movement to bring the foot 9 into operative 40 relation to the projection of said finger 16, whereby when the stepping lever 3 is again rocked to the right the retaining pawl 15 will be removed from engagement with said ratchet 4 and the same permitted to return to normal 45 condition under the influence of a spring 18.

When the ratchet reaches the end of its movement the pin 10 carried upon arm 5 rides up onto a shoulder 19 at the end of the slot 11 and said arm 5 lifts the foot 9 into operative 50 relation to the projection 17 of finger

16, so that the lever 3 may operate the retaining pawl 15. The contact spring 20 is arranged to be engaged by the ratchet at the end of its movement.

The ratchet is now restored to normal condition by the spring 18, and as the same completes its return movement a pin 21 carried thereby engages a stud 22 carried by the operating lever 7 of springs 6, and restores said lever and springs to normal condition. A lug 23 carried by the ratchet 4 is adapted when the ratchet is in normal position to engage a spring 24 and force the same into contact with its anvil. A stop 25 is carried by the ratchet to limit the return movement thereof.

The operation of the device may be briefly outlined as follows: When the magnet 1 is supplied with current of one direction, it tilts its armature 2 and rocks the stepping lever 3 to the left, causing the advance of the ratchet 4, said ratchet in leaving normal condition separating spring 24 from its anvil. Said spring and anvil may control the talking circuit of the station wherein the switch is located. When the ratchet has been advanced a number of steps corresponding to the number of the station where the same is located, for example, four steps for station No. 4 of a party line, the spur 12 will engage the pin 10, and lift the arm 5, thereby bringing the foot 9 into operative relation to the projection 8 of the operating lever 7. The magnet 1 in responding to current of opposite direction rocks the lever 3 to the right, causing the foot 9 to rock the lever 7 and close springs 6, which may complete the talking circuit at the station where the switch is located. The magnet 1 will now rock the lever 3 to the left and continue the advance of the ratchet 4, and when said ratchet has reached the end of its movement the pin 10 will ride up upon the shoulder 19 and rock the arm 5 far enough to bring the foot 9 of the lever 3 into operative relation to the projection 17 of the finger 16 of the retaining pawl, as shown in Fig. 4. Now the arm 3 may be rocked to the right and the foot 9 will operate finger 16 and remove the retaining pawl from the ratchet 4, whereupon said ratchet is returned by its spring 18 to normal condition. The lever 3 would be given this movement to the right at the end of the conversation.

I claim:

1. In a switching device, the combination 120 with a ratchet, of an electromagnetically operated stepping lever therefor, said lever when rocked in one direction advancing said ratchet, contact mechanism, an arm operated by said ratchet when advanced a predetermined distance, to cause said lever when rocked in the opposite direction to actuate said contact mechanism, and retaining mechanism for said ratchet, said arm being operated by said ratchet at the end of its 125 130

movement to cause said lever when rocked in said opposite direction to operate said retaining mechanism and release said ratchet.

2. In a switching device, the combination with a ratchet, of an electromagnetically-operated stepping lever, said lever when rocked in one direction controlling the advance of said ratchet, contact springs, a lever adapted to operate said springs, an arm 10 operated by said ratchet when advanced a predetermined distance, to cause said stepping lever when rocked in the opposite direction to actuate said second-mentioned lever, a spring-actuated retaining pawl for said ratchet, and a finger carried by said pawl, said arm being operated by said ratchet at the end of its movement to cause said stepping lever when rocked in said opposite direction to move said finger and pawl and release said ratchet.

3. In a switching device, the combination with a ratchet, of an electromagnetically-operated stepping lever adapted when rocked in one direction to advance said ratchet, contact springs, an operating lever therefor, a foot movably mounted upon said stepping lever, means operated by said ratchet when advanced a predetermined distance for moving said foot into position to engage and operate said second-mentioned lever upon the rocking of the stepping lever in the opposite direction, a retaining pawl for said ratchet, and means operated by said ratchet at the end of its movement for moving said foot into position to operate said retaining pawl upon the movement of said stepping lever in said opposite direction.

4. In a switching device, the combination with a ratchet, of an electromagnetically-operated stepping lever adapted when rocked in one direction to advance said ratchet, contact springs, an operating lever therefor, a foot slidably mounted upon said stepping lever, a pivoted arm, means operated by said ratchet when advanced a predetermined distance for moving said arm to cause the same to bring said foot into operative relation to said second-mentioned lever said lever when rocked in the opposite direction moving said foot to cause the same to operate said second-mentioned lever, and a retaining pawl for said ratchet, a finger carried thereby, and means operated by said ratchet at the end of its movement for operating said arm to cause the same to bring said foot into operative relation to said finger; whereby when the stepping lever is subsequently rocked in said opposite direction, said foot will engage said finger and release said pawl from said ratchet.

5. In a switching device, the combination with a ratchet, of an electromagnetically-operated stepping lever therefor adapted when rocked in one direction to advance said ratchet, contact mechanism, a foot upon

said stepping lever, and an arm operated by the ratchet when advanced a predetermined distance to cause said foot, when the lever is rocked in the opposite direction to actuate said contact mechanism.

6. In a switching device, the combination with a ratchet, of an electromagnetically-operated stepping lever for said ratchet, contact springs, an operating lever for said springs, a movable foot carried by said stepping lever, and an arm operated by the ratchet when advanced a predetermined distance to move said foot into operative relation to said operating lever; whereby when said stepping lever is rocked in an opposite direction said foot will move said operating lever and actuate said springs.

7. In a switching device, the combination with a ratchet provided with a slot, of an electromagnetically-operated stepping lever 85 for said ratchet adapted when rocked in one direction to advance the same, contact mechanism, an arm having a pin riding in said slot in said ratchet, said arm when operated being adapted to cause the stepping 90 lever when rocked in the opposite direction to actuate said contact mechanism, and a spur carried by said ratchet adapted when the same has been advanced a predetermined distance to engage said pin and operate 95 said arm.

8. In a switching device, the combination with a ratchet provided with a slot, of an electromagnetically-operated stepping lever adapted when rocked in one direction to advance said ratchet, contact mechanism, an arm adapted when operated to cause the said stepping lever when rocked in an opposite direction to actuate said contact mechanism, a pin carried by said arm riding in said slot in 100 said ratchet, a spur secured to said ratchet and projecting into the path of said pin to engage the same when the ratchet has been advanced to a predetermined position and operate said arm, said spur being adapted to 105 be secured to said ratchet in different positions; whereby the spur may be caused to operate said pin and arm at any desired point in the advance of the ratchet.

9. In a switching device, the combination with a ratchet provided with two concentric slots, of a shaft therefor, an electromagnetically-operated stepping lever adapted when rocked in one direction to advance said ratchet, contact mechanism, an arm adapted 115 when operated to cause the stepping lever in its reverse movement to actuate said contact mechanism, a pin carried by said arm riding in one of said slots in said ratchet, a spur loosely mounted on said shaft, said spur 120 being adapted to engage said pin and operate said arm, and a binding screw adapted to pass through the other of said slots in said ratchet and secure said spur to the ratchet to cause the same to project into the path of 125 130

said pin and engage the same at any desired point in the advance of the ratchet.

10. In a switching device, the combination with a ratchet, of an electromagnetically-operated stepping lever therefor adapted when rocked in one direction to advance said ratchet, contact springs operated by said ratchet when in its normal position, an arm operated by said ratchet when advanced 10 a predetermined distance, contact mechanism actuated by the stepping lever when rocked in a reverse direction under the control of said arm, contact springs operated by the ratchet at the end of its movement, a 15 retaining pawl for said ratchet, said arm being operated by said ratchet at the end of its movement to cause said lever when subsequently rocked in said opposite direction to remove said retaining pawl from said ratchet.
20. 11. In a switching device, the combination with a ratchet, of an electromagnetically-operated stepping lever adapted when rocked in one direction to advance said ratchet, contact springs, an operating lever 25 for said springs, an arm operated by said lever when advanced a predetermined distance to cause said stepping lever when rocked in the opposite direction to actuate said operating lever, a retaining pawl for said ratchet, 30 said arm being operated by said ratchet at the end of its movement to cause said stepping lever when rocked in said opposite direction to move said retaining pawl from said ratchet, a stud carried by the operating lever 35 of said springs, means for restoring said ratchet to normal condition, and a pin carried by said ratchet adapted as the same returns to normal position to engage said stud and restore the said operating lever and 40 springs to normal condition.

12. In a switching device, the combination with a ratchet, of an electromagnetically operated stepping lever adapted when rocked in one direction to advance said 45 ratchet, contact springs, an operating lever therefor, a movable foot upon said stepping

lever, an arm operated by said ratchet when advanced a predetermined distance adapted to engage said foot and move the same into operative relation to said operating lever; 50 whereby when the stepping lever is rocked in the opposite direction said rocking lever will be caused to actuate said springs, a retaining pawl for said ratchet, a finger carried thereby, said arm being operated by said ratchet 55 at the end of its movement to move said foot into operative relation to said finger; whereby when the stepping lever is again rocked in a reverse direction the retaining pawl will be removed from said ratchet. 60

13. In a switching device, the combination with a ratchet provided with a concentric slot, of an electromagnetically-operated stepping lever adapted when rocked in one direction to advance said ratchet, contact 65 springs, an operating lever therefor, a sliding foot on said stepping lever, a pivoted arm, a pin carried thereby riding in said concentric slot in said ratchet, a spur carried by said ratchet adapted to engage said pin at a predetermined point in the advance of said ratchet and rock said arm, said arm being adapted to move said foot into operative relation to said operating lever; whereby when the stepping lever is rocked in the opposite 75 direction said operating lever will actuate said springs, a retaining pawl for said ratchet, a finger therefor, and a shoulder formed at the end of said slot upon which said pin rides when the ratchet completes its movement to 80 rock said arm and bring said sliding foot into operative relation to said finger; whereby when the stepping lever is subsequently rocked in said opposite direction the retaining pawl will be removed from said ratchet. 85

In witness whereof, I, hereunto subscribe my name this 2nd day of October A. D., 1906.

OSCAR F. FORSBERG.
